PACKING TRAY FOR METERS

Richard L. Emery, Fairfield, Maine

Application July 28, 1953, Serial No. 26,164

Term of patent 14 years

(Cl. D58—13)

To all whom it may concern:

Be it known that I, Richard L. Emery, a citizen of the United States of America, residing at Fairfield, county of Somerset, State of Maine, have invented a new, original, and ornamental Design for a Packing Tray for Meters, of which the following is a specification, reference being had to the accompanying drawings, forming part thereof.

Fig. 1 is a top plan view of a packing tray for meters, showing my new design,

Fig. 2 is a side view thereof, partly in section, and taken on the line 2—2 of Fig. 1, and

Fig. 3 is a cross-sectional view thereof taken on line 3—3 of Fig. 1.

I claim:

The ornamental design for a packing tray for meters, as shown.
